UNITED STATES PATENT OFFICE.

HARMON O. NELSON, OF WHITINSVILLE, MASSACHUSETTS, ASSIGNOR TO WHITIN MACHINE WORKS, OF WHITINSVILLE, MASSACHUSETTS, A CORPORATION OF MASSACHUSETTS.

GEARING.

1,270,859.

Specification of Letters Patent.

Patented July 2, 1918.

Application filed February 24, 1917. Serial No. 150,652.

To all whom it may concern:

Be it known that I, HARMON O. NELSON, a citizen of the United States, residing at Whitinsville, in the county of Worcester and Commonwealth of Massachusetts, have invented certain new and useful Improvements in Gearing, of which the following is a full, true, and concise specification.

This invention to be hereinafter described relates to roving, spinning and like machines, and more particularly to means for obtaining finer changes in the draft or stretch of the material being operated on by the drawing rolls. In machines as constructed at present the draft arrangement of the rolls consists in the employment of a train of gears comprising the driving gear on the front roll, an intermediate gear meshing therein and driving a short shaft held in a bearing concentric with the front roll. To the other end of this shaft is fixed the change gear which meshes into a gear on the back roll. In this arrangement alterations in the draft between the rolls can be obtained only by using gears of different sizes for the so called change gear. Owing to the limited space that can be devoted to this gear its size is necessarily small; consequently a change of only one tooth results in altering the draft to a greater degree than is sometimes desired. In order to obtain the required draft it is sometimes necessary to change both the intermediate gear and the change gear. This necessitates employing several different swing stands, one for each size of intermediate gear which is objectionable owing to the room they take up in the mill and also on account of the work imposed on the operative in making the changes.

With this general fact in view my present invention aims to produce a more simple, efficient and reliable means for obtaining any desired draft with a minimum number of parts and the least work to the operative; and while it is herein shown and described as associated with spinning machinery, it is to be understood that the invention may be used in connection with other types of machinery requiring changes in gearing and that in its true scope, the invention is not restricted to the details or particulars as illustrated and described, but may be varied within the definition of the invention as pointed out in the claim.

In the drawings; Figure 1 shows an end elevation of the draft gearing of a roving frame with my improvement embodied thereon. Fig. 2 is a rear elevation of the same. Fig. 3 is a section on line A B of Fig. 1 showing the arrangement for maintaining the swing arm concentric with the front roll gear. Fig. 4 is an enlarged view of the swing arm. Fig. 5 is an end view of the slide for the shaft bearing of the intermediate gear. Fig. 6 is a side elevation of the intermediate gear shaft bearing.

Similar marks of reference indicate corresponding parts in all the figures.

It will be understood that the roller beam, marked 1 in the drawings, is the usual construction on which the rolls of a roving or like machine are supported, or above which they are mounted, being a longitudinal member extending the full length of the machine.

The drawings show only the ends of the drawing rolls, the front, middle and back of which are marked respectively 2, 3, and 4. These rolls are supported in the usual manner in bearings (not shown) fixed to the roller beam. As usually constructed motion is transmitted from the front roll to the back roll by a train of gears consisting of the front roll gear 5 driving the gears 6 and 7 of a compound gear, the latter gear 7 driving the back roll through its gear 8. The compound gears 6 and 7 are fixed at opposite ends of a short shaft 9 revolving in a bearing integral with the swing arm 10 which swings on a ring 11 integral with standard 12 fixed to the roller beam; the ring 11 being concentric with the front roll gear insures constant contact between the front roll and intermediate gears for all sizes of the change gear 7. When the gears 7 and 8 are properly meshed they are securely held in that state by the bolt 13 clamping the swing arm and standard 12 together.

As heretofore stated the above construction is objectionable as it necessitates a different swing arm for each size of intermediate gear. To overcome this objectionable feature I provide an adjustable bearing 14 for the compound gear shaft 9 whereby but one swing arm is required for all changes in the sizes of both the intermediate and change gears. The adjustable bearing is fitted to the slides 15 integral with the swing

arm 10 and may be securely fastened thereon by a bolt 16 clamping the foot 17 to the swing arm.

By this construction large intermediate gears may be used thus insuring a finer degree of differences in drafts obtained.

What is claimed is:

In a machine of the character described, the combination of draft rolls comprising a front and a back roll; a train of gears, transmitting motion between the rolls, comprising a gear fixedly mounted on each roll, and gears forming a compound gear meshing with the roll gears respectively; a swing

arm, the axis of rotation of which is coincident with the axis of rotation of the front roll gear; the swing arm having slides 15 integral therewith, a bearing 14 for the shaft of the compound gear, having a foot 17 adjustably mounted on the slides 15; means to securely fasten the foot to the swing arm, and means for fastening the swing arm in a fixed relation with a stationary part of the machine.

In testimony whereof, I have signed this specification.

HARMON O. NELSON.
